UNITED STATES PATENT OFFICE.

WOLFGANG HERMANN, OF CHICAGO, ILLINOIS, ASSIGNOR TO METAL SPECIALTIES MANUFACTURING COMPANY, OF CHICAGO, ILLINOIS, A CORPORATION OF ILLINOIS.

IGNITION DEVICE.

Application filed September 29, 1924. Serial No. 738,956.

This invention relates particularly to ignition devices for use in connection with electric cigar lighters, and the like.

The primary object is to provide a simple and improved device whose parts can be formed and assembled with great facility. A further object is to provide a ventilated body of insulation material which serves as a mounting for the resistance element and the circuit closing device.

The invention is illustrated in its preferred embodiment in the accompanying drawings, in which—

Figure 1 illustrates brokenly cord-winding means and a cigar lighter associated therewith, the device being well adapted to serve as a cigar lighter for use in connection with an automobile; Fig. 2, an enlarged sectional view of the ignition device, or tip, shown in Fig. 1; Fig. 3, a sectional view of a suitable form of handle for the ignition device; Fig. 4, a front side view of the ignition device; Fig. 5, a rear side view of the same; Fig. 6, a rear view of the insulation body employed and the socket member with which it is equipped; Fig. 7, a view of a spider-like guard, or protecting plate, with which the resistance element is equipped; Fig. 8, a view of a spider-like insulation member; Fig. 9, a view of a washer employed in the resistance element assembly; Fig. 10, a view of the resistance wire; Fig. 11, a view of an insulation member employed; Fig. 12, a rear view of a modified form of the ignition device; Fig. 13, a section taken as indicated at line 13 of Fig. 12; and Fig. 14, a broken prospective view of a spring segment employed as a circuit closer in the modified form of the device.

In the construction illustrated in Figs. 1 to 11 inclusive, A represents a portion of a cord-winding device mounted on a dash B; C represents a handle, or socket device, with which is connected a cord 1 which includes the electric wires; and D represents the improved ignition device which is adapted to the handle, or socket, C.

The device C, in the illustration given, comprises a tubular member 2 having secured in one end thereof a metallic socket 3. In

the illustration given, the socket 3 is provided internally with a thread 3^a adapted to receive the threaded shank of the ignition device. The member 3 is shown provided with an insulated central contact 4, the wires 1^a and 1^b of the cord are shown connected, respectively, with the socket member 3 and the central terminal 4.

The ignition device D preferably comprises an insulation body 5. This body is in the form of a suitably shaped disk 5^a having a front peripheral flange 5^b and a rear peripheral flange 5^c. The disk is further provided at its front side with a central hub-like projection 5^d and at its rear side the disk has a central stem 5^e which is encircled by a metallic socket-member 6. The member 6 preferably is secured in position in the operation of molding the body 5. The member 6 preferably has an external flange 6^a at its front end which is embedded so as to lie flush with the rear surface of the disk portion 5^a of the insulation body. The member 6 is of general tubular form and preferably has a taper bore 6^b, which, in the molding operation, becomes filled with the insulation material. The bore converges forwardly, and thus the shank 5^e is enlarged at its rear end so that it cannot be forced through the tubular member when the ignition device is screwed into the socket member 3.

The resistance element assembly is designated 7. It comprises a spiral resistance wire 7^a, an inner insulation disk 7^b, an outer spider-like insulation disk 7^c, a ring 7^d interposed between the insulation disks, and a spider-like guard, or retainer, 7^e which may be formed of sheet-metal. The disks 7^b and 7^c may be formed of mica. The spiral resistance wire 7^a has a rearwardly turned outer extremity 7^f and a rearwardly turned inner extremity 7^g. The inner extremity extends into a small tubular member 8 which forms a part of the central terminal of the device, the rear end of the member 8 receiving a screw 9 which extends through the insulation shank 5^e and whose head is adapted to contact with the central contact 4 of the socket device C. The extremity 7^g of the

wire is secured in the tubular member by a wedge-pin 10. The parts are secured together by bending the arms 11 of the blank 7^a rearwardly about the edges of the insulation disks and the interposed ring and bending the extremities of the arms inwardly so as to engage the rear surface of the underlying disk 7^b.

Within the front flange 5^b of the insulation body 5 there is afforded an open chamber 12 which is adapted to receive the resistance element assembly. The central portion of the disk 7^b is provided with a perforation 13 through which the sleeve 8 extends, and the sleeve 8 preferably is provided with a flange 8^a which overlies the central portion of the disk 7^b. The wire element 7^a lies within the plane of the ring 7^a and between the planes of the mica disks. The insulation body 5 is provided with an annular recess 14 which encircles the hub portion 5^a, so that an air space is provided back of the plane of the resistance element assembly.

The insulation body 5 is further provided within the rear flange 5^c with a shallow chamber 15 in which the spring circuit closer is mounted. There extends through the disk 5^a an eccentric metal bushing 16. The outer extremity 7^c of the resistance wire extends through this bushing and is secured by a drop of solder 17.

The insulation body 5 is further provided with eccentric ventilating perforations 18 which are located inside of the flanges of the body. Located in the chamber 15 is a spring segment 19 which has one end connected with the rear end of the bushing 16 and the other end connected with a metallic push button 20 which is adapted to work freely through a perforation in the rear flange 5^c of the body 5. In the illustration shown in Figs. 2 and 5, the spring segment 19 is in the form of a curved piece of wire having at one end a hook 19^a which engages a slot with which the rear end of the bushing 16 is provided, and having at the other end a hook 19^b which engages an annular slot with which the inner portion of the push button 20 is provided. In the form of device being described, the spring segment 19 serves to hold the bushing 16 in position and also to hold the push button 20 in position. The spring normally holds the push button out, or away from the circuit closing position. When the button is pressed, its inner end makes contact with the flange 6^a of the metallic socket member 6, and thus the circuit is closed.

In the modification shown in Figs. 12-14, the tip, or ignition device, is designated D'. The device is like the one previously described, except that the bushing 16 is replaced by a metal insert 21, and the wire

circuit closer 19 is replaced by a sheet-metal spring segment 22. One end of the segment 22 is secured, by a tubular rivet 23, to the insert 21. The other end of the segment is provided with a U-shaped head 22^a, one flange of which is provided with a perforation 22^b to which is secured the inner end of the push button 20^a. The push button extends laterally through a perforation in the wall of the insulation body. Normally, the circuit is open, but when the push button 20^a is pressed inwardly, the circuit closer 22 is forced into contact with the flange 6^a of the socket member 6.

Each of the constructions described provides a main insulation body which serves as a mounting for the resistance element and switch device and which is directly provided with a shank, or socket member, adapted for connection with any suitable socket device, such as the device illustrated in Fig. 3. The insulation body, or tip, is itself of a composition adapted to resist the transmission of heat. In addition, the body is well ventilated. Such a construction enables the tip to be held in the hand while the ignition device is being used for lighting a cigar, for example. The construction renders entirely practicable the use of a switch device in connection with the tip itself, and distinguished from the use of a switch in the handle, or a switch in connection with the cord-winding device.

The foregoing detailed description has been given for clearness of understanding only, and no unnecessary limitations should be understood therefrom, but the appended claims should be construed as broadly as permissible in view of the prior art.

What I regard as new, and desire to secure by Letters Patent, is:

1. A device of the character set forth comprising an insulation disk equipped with front and rear flanges and affording front and rear chambers, a metallic socket member projecting from the central rear portion of said body, said socket member being provided with a taper bore, insulation material in said bore, a central terminal extending through said body and through the insulation in said socket member, an eccentric metallic insert extending through said insulation body, a resistance element mounted in the front chamber and having an inner extremity connected with said central terminal and an outer extremity connected with said eccentric insert, and a circuit closing device mounted in the rear chamber and adapted to effect closing of the circuit between said eccentric insert and said socket member.

2. A device of the character set forth comprising an insulation disk equipped with front and rear flanges and affording front and rear chambers, a metallic socket member

projecting from the central rear portion of said body, said socket member being provided with a taper bore, insulation material in said bore, a central terminal extending through said body and through the insulation in said socket member, an eccentric metallic insert extending through said in-

sulation body, and a resistance element mounted in the front chamber and having an inner extremity connected with said central terminal and an outer extremity connected with said eccentric insert. 10

WOLFGANG HERMANN.
